United States Patent

Des. 241,205
Patented Aug. 31, 1976

241,205

COMBINED CUP HOLDER AND MOUNTING BRACKET THEREFOR

Milton Halsted, Long Beach, Ivan A. McIntyre, Westminster, David Y. Muramatsu, Costa Mesa, and James P. Sullivan, Tustin, Calif., assignors to Chicago Specialty Manufacturing Company, Skokie, Ill.

Filed June 3, 1975, Ser. No. 583,502

Term of patent 14 years

Int. Cl. D6—04; D23—02
U.S. Cl. D6—115

FIG. 3.

FIG. 4.

FIG. 5.

FIG. 1 is a perspective view of a combined cup holder and mounting bracket therefor, showing our new design.

FIG. 2 is a front elevational view.

FIG. 3 is a side elevational view, the side opposite being a mirror image thereof, the cups being shown in broken lines for illustrative purposes only.

FIG. 4 is a top plan view.

FIG. 5 is a bottom plan view.

We claim:

The ornamental design for a combined cup holder and mounting bracket therefor, as shown and described.
